[57] **CLAIM**

The ornamental design for a ball display, as shown and described.

DESCRIPTION

FIG. 1 is a top perspective view of the ball display; FIG. 2 is a side elevation, the remaining three sides being identical to that shown;

FIG. 3 is a plan view, the bottom of the ball display being flat and unornamented;

FIG. 4 is a side view of a second embodiment, the remaining three sides of the second embodiment being identical to that shown;

FIG. 5 is a bottom view of the ball display in FIG. 4, its plan view being identical to that shown in FIG. 3; and,

FIG. 6 is a side elevation view of the ball display in FIG. 4, showing balls in broken lines about the product for illustrative purposes only and forming no part of the claimed design.
